UNITED STATES PATENT OFFICE.

HERBERT JOSEPH POND, OF NORWICH, ENGLAND.

DESIGN FOR A TOE ATTACHMENT FOR SURGICAL PURPOSES.

SPECIFICATION forming part of Design No. 32,153, dated January 30, 1900.

Application filed December 12, 1899. Serial No. 740,130. Term of patent 14 years.

To all whom it may concern:

Be it known that I, HERBERT JOSEPH POND, a subject of the Queen of Great Britain, residing at Norwich, in the county of Norfolk, England, have invented and produced a new and original Design for a Toe Attachment for Surgical Purposes, of which the following is a specification.

In the accompanying drawings, forming a part of this specification, Figure 1 is a top plan view of a toe attachment, showing my new design. Fig. 2 is an end view, and Fig. 3 is a side view.

As shown in the drawings, the leading or material feature of my design consists of a longitudinally-extended approximately flat body portion A, from the edge of which project curved arms or loops extending at the side of said body, as shown at B and C. The loop B extends from the under edge of the body A and bridges the inner face of the same, projecting upwardly and having its top end extending toward the body and terminating in an angular projecting portion b adjacent to the top edge of the body. Said loop B is arranged near the outer end of the body A. The arm or loop C projects from

the lower edge of the body A at a point in rear of the loop B, and it projects outwardly and toward the front loop B and has its outer end curved upwardly and inwardly, as at c, toward said latter loop. A loop D is shown extending at the rear end, the ends of which loop respectively terminate at the rear end of the body A and at the rear edge of the middle portion of the loop B.

My new design has relation to toe attachments which are applied to the human foot for the purpose of relieving and curing bunions and other deformities.

Having fully described my invention, I claim as new and desire to secure by Letters Patent—

The design for a toe attachment for surgical purposes, substantially as herein shown and described.

In testimony that I claim the foregoing as my invention I have signed my name, in presence of the subscribing witnesses, this 1st day of December, 1899.

HERBERT JOSEPH POND.
